A. Marcellas.
Harvester Cutter.

No. 19936

Patented April 13, 1858.

UNITED STATES PATENT OFFICE.

A. MARCELLUS, OF AMSTERDAM, NEW YORK.

IMPROVEMENT IN TRACK-CLEARERS FOR MOWING-MACHINES.

Specification forming part of Letters Patent No. 19,936, dated April 13, 1858.

To all whom it may concern:

Be it known that I, ABRAHAM MARCELLUS, of Amsterdam, in the county of Montgomery and State of New York, have invented a new and useful Improvement in Track-Clearers for Mowing-Machines; and I do hereby declare that the following is a full, clear, and exact description of the same, reference being had to the annexed drawings, making a part of this specification, in which—

Figure 1 is a side view of a mowing-machine with my improvement applied to it, and Fig. 2 is a plan or top view of the same.

Similar letters of reference indicate corresponding parts in the two figures.

This invention consists in a novel way of operating or vibrating a plate or board which is pivoted to the shoe and fitted within the wing, at the outer end of the finger-bar of the machine, the vibrating plate or board and the wing constituting the track-clearer.

The invention relates to a modification of an improved track-clearer for which Letters Patent were granted to me, bearing date December 29, 1857. In the latter invention the plate or board was so arranged as to be operated by a cam placed on the wheel which supported the outer end of the finger-bar, and hence said invention was only applicable to large-sized machines, or such in which it was necessary to have the outer ends of the finger-bars supported by a wheel.

This invention herein described is designed to render the vibratory plate or board applicable to small or light machines, or any class of mowing-machines in which it is not necessary to have the finger-bars supported at their outer ends by wheels.

To enable those skilled in the art to fully understand and construct my invention, I will proceed to describe it.

A represents the main frame of a mowing-machine, and B is the finger-bar attached thereto.

C is the driving-wheel, which is fitted within the main frame, and D is a shoe attached to the outer end of the finger-bar, said shoe having a wing, E, attached to it.

The above parts are of usual construction, and therefore do not require a minute description.

F is a plate or board, the lower end of which is pivoted to the shoe, as shown at a. This board or plate is fitted in a slot in the wing E, and is allowed to work or vibrate horizontally therein. The board or plate has an inclined position corresponding of course to the inclination of the wing E, and the upper end of the board or plate is provided with a projecting arm, b.

To the outer end of the arm b one end of a connecting-rod, c, is attached, and the opposite end of this rod is connected to the outer end of a lever, G, which works on a fulcrum-rod, d, attached to the main frame A.

To the inner side of the driving-wheel C a zigzag flange, e, is attached, said flange forming elevations and depressions at its sides, and against the outer side of this flange, which is, in fact, a cam, the front end of the lever G bears, and is pressed against the cam by means of spiral spring f, which encompasses the rod d, and has its lower end attached to the main frame, and its upper end attached to the lever G.

From the above description it will be seen that as the machine is drawn along the cam e will move the lever G in one direction, and the spring f will move it in the opposite direction, and consequently a vibratory movement will be given the board or plate F, and the cut grass will be thrown off from the wing E toward the lever G, and an unobstructed or free space or track formed between the standing and cut grass, the plate or board being operated from the same wheel that drives the sickle or cutting device.

I do not claim separately the wing E and plate or board F, for they have been previously used; but

I claim as new and desire to secure by Letters Patent—

Operating the plate or board F from the driving-wheel C by the means herein shown, or its equivalent, for the purpose set forth.

ABRAHAM MARCELLUS.
